SHOE

Bennett Jayne, Richmond Hill, N. Y., assignor of one-half to Dominick Calderazzo, Dolgeville, N. Y.

Original application July 15, 1939, Serial No. 284,571. Divided and this application March 6, 1942, Serial No. 433,554

6 Claims. (Cl. 36—19.5)

This invention relates generally to footwear. More particularly, my invention relates to an improved construction for shoes adapted for street or sportwear and especially to the type of shoes having relatively thick resilient outer soles.

One of the objects of my invention is to provide an improved shoe construction of the character described having a skirt portion which partially conceals the thick outer sole and is so attached to the shoe that it will always present a smooth and non-bulging appearance.

Another object of my invention is to provide an improved shoe construction of the character described having skirt portions which are separate from the upper and adjacent the bottom edge thereof.

Still another object of my invention is to provide a novel shoe construction of the character described which shall comprise relatively few and simple parts, which shall be easy to assemble, which shall be relatively inexpensive to manufacture and yet rugged in construction and which, at the same time, shall be a general improvement in the art.

Other objects of this invention will in part be obvious and in part hereinafter pointed out.

Certain features shown and described but not claimed in this application are shown, described and claimed in my copending application for shoes Serial No. 284,571, filed July 15, 1939, now Patent Number 2,284,620, granted June 2, 1942, from which the present application is divided.

The invention accordingly consists in the features of construction, combinations of elements, and arrangement of parts which will be exemplified in the construction hereinafter described, and of which the scope of application will be indicated in the claims.

In the accompanying drawing, in which is shown one of the various possible embodiments of this invention and wherein like numbers refer to like parts,

Fig. 1 is a side elevational view, partly sectional, of a shoe constructed in accordance with my invention; and

Figs. 2 and 3 are cross-sectional views thereof taken substantially along the lines 2—2 and 3—3 of Fig. 1.

Referring now in detail to the drawing, 10 is a shoe constructed in accordance with my invention comprising an inner sole 12 of customary design and thick outer sole 14 made of a resilient material such as sponge rubber. The contour and design of said outer sole 14 is more fully shown and described in the said parent patent

and in my co-pending application for Outer soles for shoes, Ser. No. 433,553, filed March 6, 1942. A leather or fabric upper 16 of a suitable design is provided, said upper being attached to the insole and outsole in any suitable manner customarily employed by the art, for example, by stitching or cementing. In the illustrated form of the invention, the bottom edge of the upper 16 is turned in between the inner sole 12 and the outer sole 14 and at the same time overlies one longitudinal edge of a strip 18 soon to be described. The upper 16 is attached to the insole 12 by adhesion and the outer sole 14 is similarly attached.

The strip 18 may be fabricated from any type 15 of flexible material such as leather, fabric or rubber which may be selected to match the materials of the upper or outsole or to provide a pleasing ornamental contrast thereto. One longitudinal edge of the strip is concealed within and attached 20 to the shoe, being disposed between the turned-in edge of the upper 16 and the outsole 14 and adhered thereto. This leaves a free portion 20 extending exteriorly of the shoe 10. The said free portion 20 is bent over to freely overlie a substantial portion of the side of the thick resilient 25 outsole 14 and thus provide a free and unattached skirt.

By employing such a construction I am able to mask a substantial portion of the thick 30 resilient outsole and thus, to all outward appearances, shift the sole line downwardly a substantial amount. Such a downward shift lends a more conventional appearance to the shoe while permitting the use of the very thick outsole 14 which greatly increases walking 35 comfort. Moreover, with a free and unattached skirt, as contrasted to a fixed attached skirt, the outsole may be flexed, bulged, and bent during walking or display of the shoe without affecting 40 the smooth, flat and unwrinkled appearance of the skirt.

It will thus be seen that there is provided a device in which the several objects of this invention are achieved, and which is well adapted 45 to meet the conditions of practical use.

As various possible embodiments might be made of the above invention, and as various changes might be made in the embodiments above set forth, it is to be understood that all 50 matter herein set forth or shown in the accompanying drawing is to be interpreted as illustrative and not in a limiting sense.

Having thus described my invention, I claim as new and desire to secure by Letters Patent: 55 1. In a shoe construction, the combination

of a thick resilient outer sole, an upper, means for attaching said upper to said sole and a flexible skirt portion depending from over said sole and freely overhanging a substantial portion of the rim of said sole, said skirt portion terminating short of the bottom edge of the rim of said sole whereby to leave the lower portion of said rim exposed.

2. In a shoe construction, the combination of a thick resilient outer sole, a flexible relatively non-resilient upper, means for attaching said upper to said sole and a flexible skirt portion of relatively non-resilient material depending from over said sole and freely overhanging a substantial portion of the rim of said sole, said skirt portion terminating short of the bottom edge of the rim of said sole whereby to leave the lower portion of said rim exposed.

3. In a shoe construction, the combination of a thick resilient outer sole, an upper, means for attaching said upper to said sole and a separate flexible skirt portion depending from over said sole and freely overhanging a substantial portion of the rim of said sole, said skirt portion terminating short of the bottom edge of the rim of said sole whereby to leave the lower portion of said rim exposed.

4. In a shoe construction, the combination of a thick resilient outer sole, an upper, means for attaching said upper to said sole and a separate skirt portion comprising a flexible strip having one longitudinal edge thereof concealed within and attached to said shoe, a portion adjacent the other longitudinal edge of said strip projecting exteriorly of said shoe and depending

from over said sole and freely overhanging a substantial portion of the rim of said sole, said skirt portion terminating short of the bottom edge of the rim of said sole whereby to leave the lower portion of said rim exposed.

5. In a shoe construction, the combination of a thick resilient outer sole, an upper, means for attaching said upper to said sole, a separate skirt portion comprising a separate flexible strip freely overhanging a substantial portion of the rim of said sole and means to attach one longitudinal edge of said strip to said shoe along a line disposed above the rim of said sole, said skirt portion terminating short of the bottom edge of the rim of said sole whereby to leave the lower portion of said rim exposed.

6. In a shoe construction, the combination of an inner sole, a resilient outer sole, an upper and a strip, said strip comprising a portion there-
20 of extending inwardly of and overlying the top surface of said outer sole and permanently attached thereto leaving a portion thereof free and unattached and projecting beyond the periphery of the said top surface, said last named
25 free portion being folded downwardly to freely overlie a portion of the rim of said outer sole to thereby provide an overhanging skirt portion, and a portion adjacent the bottom edge of said upper being interposed between said insole and
30 said strip and permanently attached therebetween, said skirt portion terminating short of the bottom edge of the rim of said sole whereby to leave the lower portion of said rim exposed.
